CLAIM

I claim the ornamental design of an elevated foam roller, as shown and described.

DESCRIPTION

FIG. 1 is a top perspective view of an elevated foam roller showing my new design;

FIG. 2 is a bottom perspective view of the elevated foam roller of FIG. 1;

FIG. 3 is a front view of the elevated foam roller of FIG. 1; FIG. 4 is rear view of the elevated foam roller of FIG. 1; FIG. 5 is a left side view of the elevated foam roller of FIG. 1;

FIG. 6 is a right side view of the elevated foam roller of FIG. 1;

FIG. 7 is a top plan view of the elevated foam roller of FIG. 1; and,

FIG. 8 is a bottom plan view of the elevated foam roller of FIG. 1.
